(57) **CLAIM**

The ornamental design for a s'more building device, as shown and described.

DESCRIPTION

FIG. 1 is an isometric view of the s'more building device showing my new design;

FIG. 2 is bottom side view thereof;

FIG. 3 is a front side view thereof;

FIG. 4 is a rear side view thereof;

FIG. 5 is a right side view thereof;

FIG. 6 is a left side view thereof;

FIG. 7 is a top plan view thereof;

FIG. 8 is a bottom plan view thereof; and,

FIG. 9 is a left side view thereof with attachment.

The broken lines illustrate environmental structure and form no part of the claimed design.

1 Claim, 8 Drawing Sheets

FIG. 2

FIG. 3

FIG. 4

FIG. 5

FIG. 6

FIG. 7

FIG. 8
